UNITED STATES PATENT OFFICE.

PHILIP A. BECKER, OF NEW YORK, N. Y.

DISPLAY-LID.

1,185,165.

Specification of Letters Patent. Patented May 30, 1916.

Application filed December 16, 1913. Serial No. 807,033.

To all whom it may concern:

Be it known that I, PHILIP A. BECKER, a citizen of the United States, and a resident of New York, borough of Brooklyn, county 5 of Kings, and State of New York, have invented a certain new and useful Improvement in Display-Lids, of which the following is a full, clear, and exact specification.

This invention relates to a class of devices adapted to be used in conjunction with boxes, or the like.

My invention has for its object primarily to provide a display lid, or device designed to be movably applied upon the open top 15 of the body of a box, or other container having a lid hinged thereto, or which may not have a lid, whereby cigars and other tobacco products as well as merchandise may be exhibited for sale to avoid being 20 damaged by dust, or subjected to the drying action of the air which tend to impair the products by extracting the natural moisture therefrom. This is accomplished mainly by providing a plate of glass, or other 25 transparent material which is applied upon the open top of the body of the box in a manner to adapt it to be hingedly swung to open or closed positions thereupon.

A further object of the invention is to 30 provide a holder adapted to be detachably applied upon the lid of the box, and which is formed with two spaced ears, or lugs having apertures for removably receiving the pins of the transparent plate to permit 35 the plate to be attached to the box lid instead of the pins being inserted in the box, whereby the plate may be swung to open, or closed positions on the body of the box by moving the box lid accordingly.

With these and other objects in view, the 40 invention will be hereinafter more particularly described with reference to the accompanying drawing forming a part of this specification, and will then be pointed out in 45 the claims at the end of the description.

In the drawing, Figure 1 is a perspective view of a box with one form of display lid embodying my invention applied thereto. Fig. 2 is a fragmentary plan, partly broken 50 away, of the form of display lid shown in Fig. 1. Fig. 3 is a fragmentary perspective view, partly broken away, showing the display lid as applied to a box, and the form of holder employed in conjunction therewith 55 for permitting the display lid to be detachably fastened to the lid of the box.

The device, or display lid has a substantially rectangular plate of glass, or other transparent material, as 10, which is cut in a size suitable to fit snugly, but be freely 60 movable between the upper extending edges of the side walls 11 and 12 of the body 13 of a box adapted to contain cigars, or other tobacco products, or any kind of merchandise, whereby the goods may be prevented 65 from being damaged by the collection of dust, or the action of air, or said transparent plate may be cut in a size so as to rest upon the upper edges of all of the walls of the box, instead of between the side walls thereof, and the box may be provided with a lid 70 14 hinged to the back wall of the box.

The transparent plate 10 may be inclosed in the usual, or any preferred form of frame, as 15, in order to prevent the plate from being easily broken as well as serving as a means to secure to the plate two stationary pointed pins, as 16 and 17, or these pins may be held against displacement to the plate in any other desired manner. The pins 16 and 17 are provided upon the frame 15 so as to extend in opposite lateral directions from the ends of one of the edges of the frame, and both of the pins have pointed free ends, and extending from the front edge of the 85 frame 15 is a lug 20 adapted to be gripped between the fingers of a person for manually moving the lid to and from the body of the box.

Serving to allow a detachable sign to be 90 used in conjunction with the display lid and also to permit the display lid to be removably held to the lid of the box instead of to the body thereof, I provide a form of holder, as 23. The holder 23 has a strip 24 95 of metal, or other pliable material adapted to be disposed transversely of the lower part of the lid, and on this strip may be inscribed a suitable sign, as 24^a. Extending at an angle from the lower longitudinal edge 100 of the strip 24 is a metal flange 25 having free end portions which are bent upwardly to provide ears, or lugs 26 and 27, each of which has a hole 28 therethrough. To pivotally connect the display lid to the holder 23 105 the ears 26 and 27 are bent in opposite lateral directions with respect to the flange 25, and the rear part of the frame 15 and the pins 16 and 17 are then arranged upon the flange and between the ears so that by reversely 110 bending the ears the pins of the display lid will be received in the holes 28 thereof. In

this manner the display lid will be pivoted to the holder, and the flange 25 will serve to support the frame of the transparent plate. In order to permit the holder 23 to be detachably applied to the lid of a box, on one end of the strip 24 is an integral sleeve 29 which is formed by bending this end portion of the sleeve in substantially an L-shape so that the free end part thereof is spaced from the strip whereby the sleeve 10 may admit an edge of the box lid. On the other end of the strip 24 is an integral clip 30 which is formed by bending this end part of the strip at a right angle, and then curving the free edge of the bent part to provide a vertically disposed bead 31 which is spaced from the strip. When the holder 23 with the display lid attached thereto is applied to the lid of the box the strip 24 is positioned so that one of the side edges of the box lid will be seated in the sleeve 29, and the strip is then disposed crosswise of the lid. By the exertion of slight pressure the opposite side edge of the lid is forced between the bead 31 25 and the strip 24 for holding the lid in the clip 30. The holder 23 will thereby be detachably held upon the box lid so that when the lid is swung in directions to and from the body of the box the transparent plate 30 and its frame will be accordingly opened or closed upon the open top of the body of the box.

In the foregoing description, I have embodied the preferred form of my invention, 35 but I do not wish to be understood as limiting myself thereto, as I am aware that modifications may be made therein without departing from the principle, or sacrificing any of the advantages of this invention, 40 therefore I reserve to myself the right to make such changes as fairly fall within the scope of the appended claims.

Having thus described my invention, I claim as new and desire to secure by Letters Patent:—

1. In a display lid of the character described, a substantially rectangular transparent plate adapted to be disposed on the open top of the body of a box having a lid 50 hinged thereto, two pins extending in opposite lateral directions from the ends of one edge of the plate, means securing the pins to the transparent plate, and a holder to which the pins are removably pivoted, 55 said holder being adapted to be detachably held upon the lid of the box, and the said holder supporting the plate in a manner whereby the transparent plate will be swung to open and closed positions on the body of 60 the box when the lid is moved accordingly.

2. In a display lid of the character described, a transparent plate inclosed in a substantially rectangular frame, and adapted to be disposed on the open top of the body of 65 a box having a lid hinged thereto, two pins

extending in opposite lateral directions from the ends of one edge of the frame, and a holder to which the pins are removably pivoted, said holder being adapted to be detachably applied upon the lid of the box, 70 and the said holder supporting the plate in a manner whereby the transparent plate will be swung to open and closed positions upon the body of the box when the lid is moved accordingly. 75

3. In a display lid of the character described, a substantially rectangular transparent plate adapted to be disposed on the open top of the body of a box having a lid hinged thereto, two pins extending in opposite lateral directions from the ends of one edge of the plate, means securing the pins to the transparent plate, a holder adapted to be detachably held upon the lid of the box, and two spaced ears provided on the 80 holder, and each having a hole therein through which one of the pins of the plate is removably inserted, and said holder having a flange supporting the plate in a manner whereby the transparent plate will be 85 swung to open or closed positions on the body of the box when the lid is moved accordingly. 90

4. In a display lid of the character described, a substantially rectangular transparent plate adapted to be disposed on the open top of the body of a box having a lid hinged thereto, two pins extending in opposite lateral directions from the ends of one edge of the plate, means securing the pins to the transparent plate, a holder adapted to be detachably applied upon the lid of the box, means removably pivoting the pins to the holder, and a flange provided on the holder, and supporting the plate in a manner whereby the transparent plate will be 100 swung to open and closed positions upon the body of the box when the lid is moved accordingly. 105

5. In a display lid of the character described, a substantially rectangular transparent plate adapted to be disposed on the open top of the body of a box having a lid hinged thereto, two pins extending in opposite lateral directions from the ends of one edge of the plate, means securing the pins to the transparent plate, a strip to which the pins are removably pivoted, said strip adapted to be disposed transversely of the lid of the box to permit a sign to be displayed thereon, a sleeve provided on one end of the strip, a clip provided on the other end of the strip, said sleeve and clip serving to permit the strip to be detachably held to the lid of the box, and means provided upon the strip, and serving to removably hold the pins to the strip, whereby the transparent plate will be swung to open or closed positions on the body of the box when the lid is moved accordingly. 115 120 125 130

6. In a display lid of the character described, a substantially rectangular transparent plate adapted to be disposed on the open top of the body of a box having a lid hinged thereto, two pins extending in opposite lateral directions from the ends of one edge of the plate, means securing the pins to the transparent plate, a strip adapted to be disposed transversely of the lid of a box to permit a sign to be displayed thereon, a flange provided on the lower edge of the strip, and supporting the transparent plate, two ears, one provided on each end of the flange, and each ear having a hole 15 therein in which is inserted one of the pins of the plate for pivotally connecting the strip to the plate, and means provided on the strip for permitting said strip to be detachably held to the lid of the box, whereby 20 the transparent plate will be swung to open or closed positions on the body of the box when the lid is moved accordingly.
7. A display lid of the class described, comprising a transparent plate adapted to be disposed upon the open top of the body 25

of a box having a lid hinged thereto, a holder to which said plate is pivoted and means on the holder to removably attach the same to the lid of the box by frictional engagement with one edge of the box lid at 30 right angles to the faces of the box lid.

8. In a display lid of the character described, a transparent plate adapted to be disposed upon the open top of the body of a box having a hinged lid, a frame for said 35 plate, a holder having an end rebent to form a sleeve to engage one edge of the box lid and the other end curled to form a bead to frictionally engage over the other edge of the box lid, and pins projecting 40 from the opposite sides of the frame near the rear edge thereof to pivotally support the plate on the holder.

This specification signed and witnessed this fifteenth day of December A. D. 1913. 45
